CLAIM

I claim, the ornamental design for vehicle, as shown and described.

DESCRIPTION

FIG. 1 is a front perspective view of a vehicle, showing my new design;

FIG. 2 is a right side elevation view thereof;

FIG. 3 is a left side elevation view thereof;

FIG. 4 is a front elevation view thereof;

FIG. 5 is a rear elevation view thereof; and,

FIG. 6 is a top plan view thereof.

The broken lines depict portions of the vehicle that form no part of the claimed design.

1 Claim, 6 Drawing Sheets(56)
